UNITED STATES PATENT OFFICE.

JAMES E. ROBISON, OF DENVER, COLORADO.

COOLING SYSTEM FOR THE RADIATORS OF AUTOMOBILE ENGINES.

1,403,709.

Specification of Letters Patent. Patented Jan. 17, 1922.

Application filed October 7, 1919. Serial No. 328,956.

To all whom it may concern:

Be it known that I, JAMES E. ROBISON, a citizen of the United States of America, residing at the city and county of Denver 5 and State of Colorado, have invented a new and useful Cooling System for the Radiators of Automobile Engines, of which the following is a specification.

My invention relates to a new automatically operating frost-proof, self-heating, and self-cooling radiator apparatus for the internal combustion engines and motors of automobile, marine, and aviating engines.

And the objects of my invention are:

First: to provide a radiator apparatus that will cool the engine's circulating water in the summer time.

Second: to provide a simple and practical radiator apparatus that will cool the circulating water of the engine or motor to a very much larger extent than the radiators in common use, and that effects this result by applying cool air to the hottest points of the radiator and engine or motor.

Third: to provide means for preventing the circulating water of the radiators of automobile engines from boiling in hot weather.

I attain these objects by the mechanism illustrated in the accompanying drawings in which;

Figure 1 is a front view of an automobile radiator constructed in accordance with my invention and illustrating my improved cooling system.

Fig. 2 is a vertical sectional view of the same.

Fig. 3 is a horizontal sectional view on the line 3—3 of Fig. 1.

Fig. 4 is a perspective view of a portion of the bottom member of the radiator shell, showing the air passageway and the arched portion of the lower water reservoir.

Fig. 5 is a sectional view on the line 5—5 of Fig. 1, showing a partition which deflects the inflowing air down one side of the hollow shell and directs it back over the engine as it rises through the opposite side of the shell.

Fig. 6 is a front view of the radiator, showing an anti-freezing system connected therewith.

Fig. 7 is a vertical sectional view of the lower portion of Fig. 6.

Fig. 8 is a diagrammatic view, showing the manner of controlling the supply of gas

to the burner, and also the manner of electrically igniting the gas at the burner, and

Fig. 9 is an edge view of the door which closes the heater chamber.

Similar letters of reference refer to similar parts throughout in several views.

Referring to the drawings:

Figures 1, 2, 3, and 4 illustrate a radiator apparatus embodying my invention.

In these figures the numeral 1, designates the radiator member of my radiator apparatus which is of new and novel construction, although its area of air passageways and water conduits may be of any suitable construction or of any of the constructions in common use. I preferably use, however, the construction shown in the accompanying drawings.

The new and novel features of the radiator apparatus appertain more especially to the shell 2, that surrounds the radiating medium 1, and which is constructed as follows:

The shell 2, of the radiator comprises a hollow wall frame which surrounds the radiating medium 1, the hollow side members, as well as the hollow upper and lower members of which, form a continuous air passageway or pipe 3, of the area desired for the different sized radiators used with engines of different horse power.

The inner wall of the upper end of the shell, which fits on the upper reservoir, is partly cut away to allow a deflector or partition 4, to rest upon the upper reservoir. This deflector extends diagonally across the air passage in the upper end of the shell, and is designed to deflect the inflowing air down one hollow side wall of the shell or frame, and to deflect the air coming up the opposite hollow side wall, back over the top of the engine. The deflector 4, has a central ring 5, and its opposite ends are sprung, behind stops 6 and 7, which are secured upon the upper reservoir, the ring 5, fitting over the usual water inlet nozzle 8. By this means the deflector 4, is held in place before the shell is placed around the radiating medium, and when the shell is in place, the outer wall of its upper member holds the deflector in place.

The lower reservoir 9, of the radiator is secured to the lower edge of the radiating medium in the usual manner, and the central portion of this reservoir is arched, as shown, to form a recess or chamber 14, in which is placed a fan, when the cooling sys-

tem is employed, and a heater when the anti-freezing system is employed. The arched portion 15, is also hollow, and forms a water connection between the two horizontal portions of the reservoir.

The top strip 10, of the water trough is connected to the water circulating passages 11, of the radiator by means of slots 12, forward through its top portion 10.

10 The inner opposite walls of the arch 15, at their bottom portions are provided with water outlet nipples 8^A, the ends of which are closed by caps 8^B. See Fig. 4. These water outlets are only used in the winter time in 15 connection with the radiator water heating apparatus, which will be presently described.

The lower member of the shell is provided with an opening 18, that communicates with the fan chamber 14, and a fan 19, is placed in 20 the chamber directly over the opening.

This fan 19, is secured on a shaft 20, that is journaled in end plates 21, and 21^A, in position over the aperture 18, the end plates being bolted together and having flanges 25 which fit in the recess 14. The fan is made to fit closely, but revolvably in the arched chamber 14 of the reservoir 9.

The shaft 20 of the fan 19, is provided with a coupling 22, at its inner end, by which 30 it is coupled to the end of a shaft 23 that is supported by a bearing 24, that is formed in a housing 25, that is attached to the adjacent side of the radiator.

On the driving shaft 23, a second fan 26, 35 is secured, and the shaft 23, extends beyond the housing far enough to receive a small pulley 27, from which a belt 28, extends to a pulley 29, that is mounted on the crank shaft 30, of the engine, which rotates the 40 shaft and its two fans.

The fan 26, is enclosed at its outside end along its lower edge by the housing 25, the upper end of which is open. This housing 25, is provided with apertures 26^B in its side, 45 and this fan draws air from all around the sides of the engine through these apertures 26^B into the housing and forces it upwardly against the overhanging end of the upper reservoir of the radiator, which is always 50 the hottest part of a radiator, and also against the pipe members that connect the radiator with the engine or motor and against the adjacent or front end of the engine. This fan also forces the cool air entering through the honey comb interstices of the radiator upwardly, so that they are directed to flow over the top portion of the engine, and thus I apply the cool air to the 55 very hottest parts of the radiator and the engine and their connecting pipe fittings.

In the front side of the upper member of the shell and on opposite sides of the filling nozzle 8, are formed openings 32, and the suction fan draws cool atmospheric air in 65 through these openings 32, into the air pas-

sageway of the shell, where it strikes the deflector 4, which directs it down the side passage 33, of the shell, whence it passes into the lower passage and across the opening 18, over which the fan 19, is placed, up the opposite side passage 34, to the rear side of the deflector 4, by which its course is deflected, and it passes out through the rear side of the air passage, which is left open for that purpose, as shown at 36^A, Figure 2. 70 The shell is formed with a horizontal, rearwardly extending plate 37, which lies slightly above the top of the upper reservoir 38, and the air which is forced up behind the deflector 4, passes out between the plate 37, and the top of the reservoir 38, the rear portion of the plate being downwardly curved as shown at 40, to give the air a downward direction. After passing from under the plate 37, the cool air flows along under the hood 80 of the engine rearwardly in contact with and over the engine; thus in addition to the cooling effect that the cool atmospheric air would naturally have on the surrounding edges of the radiator, it quite measurably 90 assists in directly cooling the engine in hot weather, which is the time of the year that it is my intention to use a fan in the arched chamber 14, in the bottom of the radiator.

The above description relates directly to 95 the arrangement of the radiator for hot weather use, some of the minor parts of which are removed when cold weather comes on and are replaced with means for heating the circulating water of the radiator 100 instead of cooling it as in the hot weather period of the year.

The description of the water heating elements, of the invention are as follows:

The fan 22, is removed from the arched recess and in its place I put a water circulating hollow conical casing 41, the opposite base portions of which are connected by suitable pipes 9^D, and couplings 9^E, with the water outlets 8^A. The conical casing 41 110 is heated by a gas burner 42. I preferably use the Prest-O-Light gas commonly used for lights of automobiles and a burner suitable for burning with a bright flame that character of gas. This burner is secured to 115 the bottom wall of the lower member of the shell by a plate 9^F, and it projects up through the opening 18 and into the hollow central space 48, in the conical casing 41. A pipe 9^C is connected to one end at the lower 120 end of the burner and leads to the Prest-O-Light cylinder, which is generally secured upon the running board of the automobile.

To the top of this conical water circulating casing is connected a pipe 43, which 125 extends up to and is connected at its opposite end to one side of a water inlet angular fitting 44, that is connected to the upper reservoir 38, of the radiator which projects rearwardly a short distance from the honey- 130

- comb air and water portion of the radiator towards the engine. This connecting pipe 43, effects a complete circulation of the heated radiator water from the conical water 5 circulating casing 41, up to the reservoir 38, and down through the honeycomb water passageways into the lower reservoir 9, and thence into the heated conical casing and up through the pipe 43, through the fitting 44, 10 into the upper reservoir 38, of the radiator. This pipe 43, is only used in the winter time, consequently in the summer time its lower end is disconnected from the casing 41, the outlet of which is closed by a cap 46. 15 In order to protect the gas burner from the cool air that would flow to it from the front of the radiator I hinge a glass door 50, to one side of the outside surface portion of the looped recess 14, and secure a 20 closing keeper 51, on the opposite side of the recess and a latch device 52, on the glass door that enables the glass door to be closed over the opening into the recess and its lamp. I also place on the opposite side of the 25 arched recess 14, a plate 21^a, that is mounted on the fan shaft and is provided with an inwardly projecting annular flange 54, that fits into the recess 14, against its inner wall, and thus closes this inner end of the recess. 30 A water outlet angular pipe fitting 55, is secured to the lower reservoir 9 on its inner side that receives the circulating pipe connections that extend to the engine water circulating jacket. The heated air that naturally flows to the rear end of the engine 56, is deflected by a plate 57, that is arranged at the rear portion of the engine to deflect this constantly accumulated heated air underneath the dash board 58, and over the 35 transmission case in such a manner as to deflect and lead the said air into the atmosphere underneath the automobile. 40 This heat deflecting plate may consist of any suitable material, but is preferably a piece of thin sheet metal and it is arranged and secured in the different makes of automobiles in any suitable manner. 45 The use of this heat deflecting plate enables the continuous discharge of the heated air from the space around the engine and within the engine's covering hood and it allows a continuously flowing stream of cool air to flow from the atmosphere in front of the automobile directly through the radiator 50 into the space under and within the hood and on all sides of the engine or motor to the atmosphere underneath the car. 55 The gas burner is arranged to be lighted from the dash board by a spark from an electric circuit connected to a battery or generator of an automobile. I illustrate a 60 diagrammatical view of the electrical connections in which 59, represents a push button on the dash board 58, and 60, a wire having a contact 60^a in line with and adjacent to the push button, which wire extends therefrom to one pole of a battery 61, a wire 62, extends from the other pole of the battery, and terminates at a point between the forked ends of the burner 42. A wire 63 70 also terminates at one end between the forked ends of the burner, and adjacent to the end of the wire 62, leaving a spark gap between the said ends of the said wires 62, and 63, and the other end of the wire 63, terminates in a contact 64, in line with, and adjacent to the push button contact. Thus when the button 59 is pushed in, the contacts 60^a and 64, close a circuit through the battery 61, and produces a spark in the gap between the terminal ends of the wires 62, and 63, which ignites the gas flowing from the burner. 75 The flow of the gas to the burner is also controlled from the dash board through an 80 adjusting rod 65, that is connected to a valve 66, that is placed in the supply pipe that extends from the Prest-O-Light cylinder 67. 85 The heating mechanism not only keeps the circulating water from freezing, but the heated air in the arched chamber is utilized to assist in maintaining the temperature in the radiator, and this is accomplished in the following manner: 90 The openings 32, in the upper end of the 95 radiator shell are closed in any suitable way, as by glass plates, and the deflector plate 4, is removed. The air heated by the burner has a natural tendency to rise, and its only escape is through the opening 18, and up 100 the hollow side members of the shell and out through the opening 36^a, where it mingles with the air passing through the radiator, and which passes over the engine and out under the plate 57 to the atmosphere. By 105 this means the hot air assists in maintaining a suitable temperature in both the lower and upper reservoir, and also heats the radiator along its side edges. 110 My invention provides a combined apparatus for hot and cold weather use, and also that embodies a complete ventilating system from the atmosphere in front of and through the radiator which creates a circulation through the entire space occupied by the 115 motor to the atmosphere under the automobile, and an electric ignition push button controlled circuit, as well as a gas control, at the dash board within reach of the chauffeur. 120 The operation of the several cooperating features of my invention have been amply described in the description of its cooperating and coacting features and need not be repeated here. 125 My invention provides a new and a complete cooling and heating apparatus for hot and cold weather use for automobiles that is under full and complete control of the chauffeur from his seat in the automobile, 130

and while I have described and claimed the preferred construction and arrangement of my invention, I do not wish to be limited thereto, as changes may be made therein 5 without departing from my invention.

Having described my invention what I claim as new and desire to secure by Letters Patent, is:

1. In a cooling system for the circulating 10 water of the engines of automobiles, the combination with the water circulating and the air cooling passageways that form the main body portion of the radiators of automobiles and the engine, of an enclosed water 15 trough along the bottom of said radiator provided with slots through its top, through which water enters said trough from said radiator, and having an enclosed upwardly extending recess portion formed in the center 20 of its length and extending across it and around which said radiator water flows, said recess having a semicircular or arched top portion, a fan mounted concentric to said recessed portion and means for rotating said 25 fan, an air pipe arranged in the shell of said radiator and surrounding the outside surface of said radiator, said air pipe being provided with an aperture in its top opening into the recess of said trough, said air pipe 30 around said radiator being provided with inlet apertures in the outside surface of its top portion, and with an air outlet on its opposite side, and a fan mounted in the recess of said trough and positioned over 35 and to cover the opening in said air pipe and adapted to draw cool atmospheric air into said pipe and force it through it and discharge it over said engine.
2. In a cooling system for the circulating 40 water of the engines of automobiles, the combination with the water circulating and the air cooling passageways that form the main body portion of automobiles and the engine, of the radiator provided with a 45 water filling nozzle at its top and with a water trough along the bottom of said radiator provided with slots through its top, through which water enters said trough from said radiator, and having an enclosed 50 upwardly extending recess portion formed in the center of its length and extending across it and around which said radiator water flows, and having pipe connected and closed outlets in its opposite sides, said 55 recess having a semicircular or arched top portion, a fan mounted concentric to said recessed portion and means for rotating said fan, a shell surrounding said radiator provided with an air passageway extending 60 entirely around it and along the underside of said trough; said air passageway in the shell of said radiator being provided with an air inlet apertures on opposite sides of said nozzle in its outside surface and with 65 an air outlet on its opposite or inside sur-
- face; a fan mounted in the recess of said trough and positioned over and to cover the opening in said air passageway, and adapted to draw cool air into and force it from said radiator over said engine, said fan being 70 supported on a shaft extending through and beyond the inner side of said recess, a second fan mounted on said fan shaft and means including a belt and pulley operated by said engine for rotating said fans and their 75 supporting shaft.
3. In a cooling system for the circulating water of the engines of automobiles, the combination with the water circulating and the air cooling passageways that form the 80 main body portion of the radiators of automobiles and the engine, said radiator being provided with a water inlet nozzle at its top, of an enclosed water trough along the bottom of said radiator provided with slots 85 through its top through which water enters said trough from said radiator, and having an enclosed upwardly extending recess portion formed in the center of its length and extending across it and around which said 90 radiator water flows, said recess having a semicircular or arched top portion, a fan mounted concentric to said recessed portion, and means for rotating said fan, an air passageway extending along the underside of 95 said trough and surrounding said radiator provided with an aperture in its top opening into the recess of said trough, said air pipe or passageway around said radiator being provided with air inlet apertures in its 100 outside surface or opposite side of said nozzle, a diaphragm across said air passageway adjacent to said air inlet apertures and arranged to close said pipe on one side of said air inlet apertures, and an air outlet 105 in said pipe opposite to said diaphragm, and a fan mounted in the recess of said trough and positioned over and to cover the opening in said air passageway, said fan being 110 supported on a shaft extending through and beyond the inner side of said recess, a second fan mounted on said fan shaft and means for rotating said fans and their supporting shaft, a housing around the outside and lower edge of said second fan, open at its 115 top end, said fan supporting shaft extending opposite to said automobile engines, and means including pulleys and a belt for connecting said fans supporting shaft to the crank shaft of said engine, whereby cool air 120 is drawn from the atmosphere and is circulated around the shell of said radiator and discharged towards and over the said engine.

In testimony whereof I affix my signature in presence of two witnesses.

JAMES E. ROBISON.
